Primary Examiner—A. Hugo Word*Assistant Examiner*—Robin V. Taylor*Attorney, Agent, or Firm*—Richard B. O'Planick; Lisa B. Riedesel[57] CLAIM

The ornamental design for a handle portion of a laundry basket, as shown and described.

DESCRIPTION

FIG. 1 is a top right front perspective view of a handle portion of a laundry basket showing my new design. The broken line showing of a laundry basket is for illustrative purposes only and forms no part of the claimed design;

FIG. 2 is a front elevational view thereof;
FIG. 3 is a left side elevational view thereof; the right side elevational view being a mirror image;
FIG. 4 is a rear elevational view thereof;

FIG. 5 is a top plan view thereof; and,
FIG. 6 is a bottom plan view thereof.
